UNITED STATES PATENT OFFICE.

STILLMAN A. CLEMENS, OF CHICAGO, ILLINOIS; ONE-HALF ASSIGNED TO
JAMES J. WALWORTH.

IMPROVEMENT IN MACHINES FOR STRAIGHTENING, BREAKING, AND CLEANING FLAX-STRAW.

Specification forming part of Letters Patent No. **59,501**, dated November 6, 1866.

To all whom it may concern:

Be it known that I, STILLMAN A. CLEMENS, of Chicago, in the county of Cook and State of Illinois, have invented a new and useful Improvement in Machines for Breaking and Cleaning Flax and other Fibrous Plants; and I do declare the following to be a full, clear, and exact description of the same, reference being had to the accompanying drawings, making part of this specification, of which—

Figure 1 is a plan of the machine, and Fig. 2 is an elevation of a longitudinal section of the machine, the same letters referring to like parts in both figures.

My invention consists in a herein-described mechanical device for drawing, straightening, and extending tangled flax, whereby a thick layer of tangled flax-straw is drawn and extended into a thin, even sheet of straightened and parallel stalks, for the purpose of preparing it for an effectual and rapid subsequent mechanical breaking of the flax-stalks; and my invention further consists in the combination of the herein-described mechanical devices for drawing and straightening tangled flax-straw with the herein-described mechanical devices for breaking the stalks of the drawn and straightened flax-straw, thus making a combined machine for the purpose of drawing and straightening and breaking tangled flax-straw at one operation; and my invention further consists in herein-described mechanical devices for scutching, beating, and picking or cleaning broken flax, and the combination of the herein described and named devices for cleaning broken flax with the before-mentioned mechanical devices for first drawing and straightening and breaking the flax-straw, thus making a combined machine for the purpose of drawing and straightening and breaking and cleaning flax at one operation.

In the accompanying drawings, *a* is the frame of the machine, of which *b* is a feed-table, *c c* being side boards of the latter; and *d* is a toothed or gill cylinder, the long-pointed teeth *e e* of which are set pointing backward from the direction in which the cylinder revolves, as shown by the arrow *f*.

A smooth or plain surfaced roller, *g*, for impaling flax upon the teeth of cylinder *d*, has its surface nearly in contact with the points of

the teeth of cylinder *d*. Successive pairs of fluted rollers are represented by *h h h h*, which are made of the form and adapted in such connection as is common with fluted rollers used to break flax. A pair of plain pressure-rollers, *j j*, with the fluted rollers and the plain roller *g*, each revolve as indicated by the arrows *i i*, &c. A breast or shell, *k*, is supported below, and its beveled upper edge fits the whole length of the surface of the lower roller *j*. The scutching and picking cylinder *l* has open heads *m m*, fastened on a shaft, *p*, which support staves *n n*, with attached tooth-plates *o o*, which are made with curved indentations and toothed points on their outer edges, as shown in the drawings.

The toothed points of the plates *o o*, by alternation in their attachments to the staves *n n*, are made to sweep all points of the circular plane in which they move, as is done in setting picker-teeth, and they move at their points closely to the surface of the lower roller *j*, and also to the adjacent side of the breast *k*, which is curved to the circle of their movement.

The arrow *q* shows the direction in which the cylinder *l* revolves. The staves *n n*, &c., are separated by narrow spaces *r r*, through which openings, when the cylinder revolves, currents of air pass outward in front of the plates *o o*.

Heads *s s* of an open concave attachment to *l* support the ends of bars *t t*, which extend the length of the cylinder, with their straight inner edges near the sweep of the tooth-points of *o o*, and their surfaces are inclined, as shown in the drawings.

Inclosed within the frame is the chute-bottom *u*, which is covered above by the bonnet *v*, which may be attached by hinges *w w* to a cover, *x*, which is over the cylinder *l*, the bonnet and cover being removed in Fig. 1.

y is a toothed or gill cylinder, which revolves as shown by the arrow *z*.

Openings *a' a'* in the bonnet *v* are for the escape of air from the inclosed space below.

b' b' are a pair of pressure and drawing rollers, whose axes are in a plane inclined to the horizon, as shown in the drawings, and they revolve in the direction of the arrows *i i*. The upper roller *b'* is a plain-surfaced roller, and the lower roller *b'* is made with narrow shal-

low channels lengthwise on its surface, not deep enough for flutes, and used to give more adhesion to material passing between them than plain rollers would give.

c' is a breast like *k*, fitting to the lower side of the bottom roller *b'*. *d'* is an open concave attachment to cylinder *g'*, with the alternating bars *e' e'*, made with curved indentations and toothed points on their inner edges next the cylinder, like the plates *o o*, while the alternating bars *f' f'* have straight inner edges, all the bars having their sides radial to the beating and picking cylinder *g'*, which last is also furnished with alternating plates *h' h'* (like the plates *o o*) and straight inner edged plates *i' i'*, and is made without openings on its surface for the production of air-currents, as was described of the cylinder *l*. The plates and bars of the cylinder *g'* and its concave are situated in respect to the lower roller *b'*, to the breast *c'*, and to each other like those of cylinder *l* and its like connections.

The arrow *j'* shows the direction in which the cylinder *g'* revolves. *k*, which is removed in Fig. 1, is a cover over *g'*, and *l'* is a cut-off or deflecting-board, extending in an inclined position in front of *g'*, with its lower edge just clearing the points of the teeth of the cylinder.

The toothed cylinder *d* revolves with a slow motion to allow a continuous thick layer of tangled flax-straw to be supplied to it by hand-feeding, and the top roller *g* revolves with a surface movement equal to or somewhat faster than that of the points of the teeth of cylinder *d*. The fluted rollers *h h* revolve with equal speed in all the pairs, be they more or less in number, and their surface movement is several fold greater than that of the tooth-points of *d*. The rotary speed of the plain rollers *j j* is regulated relative to that of the fluted rollers so that the former shall take away the thin sheet of broken flax as fast as it is delivered from the latter, and no faster. The cylinder *l* revolves with many fold greater surface speed than that of the rollers *j j*, and the cylinder *g'* revolves in like proportion faster than the rollers *b' b'*, which last-named rollers move much faster than the tooth-points of cylinder *y*.

Motive power being applied to the shaft *p*, or to any other of the axes of the machine, the relative motions are communicated to the operating parts of the combination by the following connections, viz: A spur-wheel, *m'*, on the axis of *l*, drives a spur-wheel, *n'*, on the axis of the lower roller *j*, which at its opposite end has a small spur-wheel, *o'*, which engages an intermediate spur-wheel, *p'*, (partly concealed by overhanging parts in the drawings,) which engages a spur-wheel, *q'*, on the axis of the lower fluted roller *h* of the forward pair of fluted rollers, from which, by an intermediate spur-wheel, *r'*, (partly concealed in the drawings,) motion is given to a spur-wheel, *s'*, on the axis of the lowermost of the back pair of fluted rollers *h h*, (otherwise designated as the first pair of fluted rollers.)

On the other end of the same lower fluted roller a spur-wheel, *t'*, gears with a larger intermediate spur-wheel, *u'*, which is coupled to a small spur-wheel, *v'*, which drives a large spur-wheel, *w'*, on the axis of the toothed cylinder *d*. At the opposite end of the axis of *d* a grooved pulley, *x'*, by a cross-band, *y'*, passing over it and a grooved pulley, *z'*, on the axis of the roller *g*, gives motion to the latter.

The rollers *j j* are geared together by the spur-wheels *a' a''*. Motion is given to the cylinder *g'* by means of a connecting-band, *c''*, passing over the grooved pulley *b''* on the axis of cylinder *l* and over the pulley *d''* on the axis of cylinder *g'*. On the opposite end of the latter a spur-wheel, *c''*, drives a spur-wheel, *f''*, on the axis of the lower roller *b'*, which at the opposite end has a geared connection with the upper roller *b'* of the same pair by the spur-wheels *g'' g''*. By means of a band, *h''*, passing around a grooved pulley on the axis of the lower roller *b'*, and on the same end inside of the lower spur-wheel *g''*, (not fully shown in the drawings,) and also around and over a larger grooved pulley, *i''*, on the toothed cylinder *y*, a slow motion is given to the latter.

In operating the machine, tangled flax-straw is spread by workmen in a thick layer upon the feed-table *b*, and advanced to the teeth of the cylinder *d*, which receives it upon its teeth and carries it forward under the surface of roller *g*, which more effectually impales it upon the teeth of cylinder *d*, from whence it is seized and drawn away by the first pair of fluted rollers, *h h*, the combined action of the cylinder-teeth and of the said fluted rollers serving to draw, comb, straighten, and extend into a thin, even sheet of straight parallel stalks the thick layer of tangled flax-straw.

The flax passing between the fluted breaking-rollers at high speed is broken more effectually and rapidly in consequence of the previous drawing and straightening action which presented it to the breaking-rollers following the drawing-rollers in a thin, even sheet of stalks made straight and parallel to the line of movement of the sheet and moving forward at high speed.

From the breaking-rollers the flax passes to and between the plain pressure-rollers *j j*, which carry and hold the broken flax to the scutching and picking action of the toothed plates *o o* of the cylinder *l*.

The plain rollers *j j* are used following the fluted rollers for the purpose of preventing the flax from winding around the lowermost of the last pair of fluted rollers, which is the tendency when fluted rollers alone are used to break flax, and when they are run at high speed, and which is also the tendency when fluted rollers are used to deliver broken flax to the action of cylinder *l*, or similar cleaning-cylinders. The lower roller *j* is made plain-surfaced, and the edge of the breast *h* is fitted close to its surface on the side toward the cylinder *l*, which deflects the air-currents caused

by the revolution of *l* from the lower roller *j*, and prevents the flax fibers from passing down under and around it to wind upon it. The breast *k* also serves by its curved face (which is close to the circle of the movement of the points of the teeth of cylinder *l*) to keep the flax within the circle of the sweep of the teeth while it is held by the rollers *j j*.

When the flax is released by the rollers *j j* it is carried down and around the cylinder *l* by its teeth and scutched against the inner edges of the bars *t t* of the concave to cylinder *l*, and the shives separated from the fiber are thrown off the cylinder and escape downward between the bars *t t*.

The flax carried around by the teeth of cylinder *l*, after passing the last of the concave bars *t t*, by the centrifugal action and the air-currents through the slotted openings *r r* is thrown off from the teeth, and, being directed upward by the chute-bottom *u*, it is impaled upon the pointed teeth of the gill-cylinder *y*, from whence it is seized and drawn away by the rollers *b' b'*, the combined action of the latter with that of the gill-teeth serving to draw, comb, disentangle, and straighten the flax fibers, and hence they are advanced and held by the rollers *b' b'* in a more favorable condition for the beating and picking action of the alternate straight-edged plates and the curved toothed plates of cylinder *g'*.

When disengaged from the rollers *b' b'*, the flax is carried down and around cylinder *g'* by the toothed points, and scutched by being drawn over the edges of the straight-edged plates *f' f'* of the concave *d'*, while the alternating toothed plates *e' e'* of the concave open and slightly detain the fibers, by which they are subjected to an additional action from the cylinder *g'*. The shives freed from the fiber escape downward between the concave bars, while the flax passing inside the latter and past the last concave bar is thrown from the cylinder *g'* upward and outward in the form of tow, the inclined board *l* serving to deflect the air-currents which bear away the fiber, and thus aid in the delivery of the material from the cylinder.

The operation of the machine is thus shown to comprise three different but combined processes—that is to say, drawing and straightening tangled flax-straw as a preparatory process to the second process of breaking the stalks, which last process is preliminary to the final process of cleaning the flax fiber; and these different processes are produced by devices susceptible of separate use.

The top feed-roller, *g*, or its mechanical equivalent, is not indispensable to a degree of utility in the use of the toothed cylinder *d*; but by its action in forcing the fibrous material between the teeth of the latter the flax is better received from the feed-table and more evenly straightened and attenuated by the drawing action of the first pair of rollers, *h h*, or other drawing-rollers in other modifications, as set forth.

The devices described for drawing and straightening the flax are applicable, with similar useful results to those described of them, to be attached to or combined with other flax-breaking or to other flax breaking and cleaning machines in use, (which differ from that described;) and they may be so combined and used when said breaking or breaking and cleaning machines are made to receive the flax at one end and to discharge it at the other end, and are so constructed and adapted as to have (by means and modes well known to mechanics) the toothed cylinder *d*, with suitable rotary movement, attached to them as feed-cylinder, from which flax-straw fed to it is drawn from it by the breaking or feed device of the machine; or when said machines are so constructed and operated as to have, by common mechanical means and modes of attachment, the toothed cylinder *d* and drawing-rollers *h h* attached to them in such manner and with such connections and rotary movements as to deliver the drawn and straightened flax-straw from the said drawing-rollers to said machines suitably for their breaking or breaking and cleaning the flax.

The toothed cylinder *d*, for its described purposes, may be connected with reciprocating rotary rollers which only act as drawing-rollers, or with reciprocating rotary fluted rollers which act as both drawing and breaking rollers, both kinds giving an intermitting drawing action, as is done in several known flax-breaking machines; and the cylinder *d*, in such connection, may have, by known means of gearing, either a continuous rotation or an intermitting rotation to correspond to and in the direction of the draft of the drawing or drawing and breaking rollers.

Furthermore, the described combined processes of drawing and straightening and breaking flax is effected by devices which may be detached from the machine and be used separately as a flax-breaker without cylinder *l* and the flax-cleaning devices following it.

When the drawing and breaking devices are so detached, they may be used to deliver the broken flax to various known machines adapted for cleaning flax by revolving scutchers and cleaners, the connection being made by common means and modes of connecting feed or breaking rollers together or to revolving cylinders for cleaning broken flax, and so familiar to mechanics as not deemed necessary to be described.

The roller *g* may be longitudinally or circumferentially ribbed on its surface to impale the flax more effectually below the tooth-points of cylinder *d* than when smooth-surfaced.

An equivalent feed and drawing apparatus to cylinder *d* may be used in place of it, said apparatus consisting of a toothed endless sheet or a series of toothed bars linked together or otherwise made to advance in regular succession, with a slow motion, toward the drawing-rollers *h h*, said apparatus being made and adapted by well-known modes so as to receive

tangled flax-straw fed to it or deposited on a feed carrier or table, from which the teeth take the material and carry it to the drawing-rollers, which draw the flax between its teeth, untangling and straightening it.

The drawing-rollers *h h* may be made, either or both of them, fluted or plain-surfaced, or with narrow shallow grooves or creases cut lengthwise on their surfaces, not deep enough for flutes; and when both are fluted they act, in the described connection, as both drawing and breaking rollers, crimping the flax-stalks in the mesh of the flutes, and breaking the woody part into short pieces or shives; and when one roller is smooth-surfaced, or creased, or lightly grooved, the rollers in the described connection act only as drawing-rollers and to crush and flatten the stalks.

The rollers *j j* may be, either or both of them, plain or smooth surfaced, or with narrow shallow channels or creases cut lengthwise on their surfaces, and may be used to deliver broken flax from breaking-rollers of common flax-breakers in the manner described of them in their connection with fluted rollers *h h*, and for the same purpose. They may be dispensed with as delivery-rollers from fluted rollers, as described of them, and also as delivery and feed rollers placed between fluted rollers and a cleaning-cylinder, as described of them; but their use in both cases is beneficial for the purposes described.

The cylinders *g'* and *l* may be used interchangeably, or both of them be made with closed surfaces, like *g'*, or with openings in their surfaces, like *l*; and either of them may have all their plates either toothed or plain-edged, as described; or rows of picker-teeth, alternating with straight-edged plates, may be used on either of them.

The concaves, or the different kinds of bars of the concaves described, and their different modes of adjustment may be used interchangeably in connection with either cylinder.

Any other common picking, scutching, or beating cylinder for cleaning flax fiber may be used when connected with the fluted rollers for breaking by the rollers *j j*, which operate as described.

The toothed cylinder *y* may be dispensed with, the rollers *b' b'* receiving the flax as it is thrown to them by cylinder *l*, to facilitate which the chute-bottom *u* has its top edge thrown backward to the position indicated by dotted lines *x''* in the drawings.

Both the rollers *b' b'* may be either plain-surfaced or channeled or creased lengthwise, as described of the lower roller *b'*.

The chute-bottom *u* and rollers *b' b'*, with or without cylinder *y*, may be used to connect any known toothed cylinders or beaters suitable for cleaning flax, similarly as they connect cylinders *l* and *g'*, and for the same purposes.

I claim as new and of my invention—

1. In a machine for drawing and straightening tangled flax-straw, used either alone or

in combination with machinery for breaking or breaking and cleaning flax, the employment of a toothed cylinder or toothed carrier, combined with drawing or drawing and breaking rollers of any kind, and with or without a device or devices for impaling the said material upon said toothed cylinder or carrier, when said cylinder or carrier and drawing-rollers are adapted to untangle, draw, and straighten said material, for the purposes set forth.

2. The employment of a flax-impaling device or devices, substantially such as described, adapted to give impalement of the stalks of tangled flax, substantially as described, upon and between the teeth of a toothed cylinder or its equivalent, or below the teeth-points to or near their base, when such toothed cylinder, is so combined with drawing-rollers or fluted drawing and breaking rollers as to convey or present the said impaled material to the action of said rollers in the said condition of impalement, for the purposes set forth.

3. The cylinder *d* and roller *g*, combined with the adjacent pair of fluted rollers *h h*, substantially as described, and for the purposes set forth.

4. The cylinder *d* and roller *g*, combined with a series of pairs of fluted rollers, *h h h h*, substantially as described, and for the purposes set forth.

5. The combination of cylinder *d* and roller *g* with drawing-rollers, either fluted or plain, in combination with one or more pairs of fluted rollers for breaking flax, substantially as described, and for the purposes set forth.

6. The rollers *j j*, in connection with fluted breaking-rollers *h h*, of one or more pairs, the whole operating substantially as described, and for the purposes set forth.

7. The combination of cylinder *d* and roller *g* with drawing and breaking rollers and the rollers *j j*, substantially as described, and for the purposes set forth.

8. The combination of cylinder *d* and roller *g* with drawing and breaking rollers and the flax-cleaning cylinder *l*, substantially as described, and for the purposes set forth.

9. The combination of cylinder *d* and roller *g*, or any of the described flax-impaling devices, with drawing and breaking rollers and the rollers *j j* and the flax-cleaning cylinder *l*, substantially as described, and for the purposes set forth.

10. The toothed cylinder *d*, combined with the adjacent pair of fluted rollers *h h*, substantially as described, and for the purposes set forth.

11. The cylinder *d*, connected with drawing-rollers, either fluted or plain, in combination with fluted rollers for breaking flax, substantially as described, and for the purposes set forth.

12. The combination of cylinder *d* with drawing and breaking rollers and the rollers *j j*, substantially as described, and for the purposes set forth.

13. The combination of cylinder *d* and drawing and breaking rollers and the flax-cleaning cylinder *l*, substantially as described, and for the purposes set forth.

14. The combination of cylinder *d*, with drawing and breaking rollers and rollers *j j*, with the cleaning-cylinder *l*, substantially as described, and for the purposes set forth.

15. The combination of fluted rollers *h h*, of one or more pairs, the rollers *j j*, the breast *k*, and cleaning-cylinder *l*, when the whole operate together, substantially as described, and for the purposes set forth.

16. The rollers *b' b'*, in connection with the chute-bottom *u* and cylinder *g'*, substantially as described, and for the purposes set forth.

17. The combination of gill-cylinder *y*, rollers *b' b'*, and cleaning-cylinder *g'*, substan-

tially as described, and for the purposes set forth.

18. The combination of toothed cylinder *d*, top roller *g'*, drawing and breaking rollers *h h h h*, rollers *j j*, breast *k*, cleaning-cylinder *l*, concave *s*, chute-bottom *u*, gill-cylinder *y*, drawing-rollers *b' b'*, breast *c'*, cleaning-cylinder *g'*, concave *d'*, and deflecting-board *l''*, all substantially as described, and for the purposes set forth.

19. The cylinder *l*, combined with cylinder *y* and rollers *b' b'*, substantially as described, and for the purposes set forth.
